UNITED STATES PATENT OFFICE.

JOHN C. SCHAFER, OF TIFFIN, OHIO, ASSIGNOR TO SCHAFER ENGINEERING & EQUIPMENT CO., OF PITTSBURGH, PENNSYLVANIA, A CORPORATION OF PENNSYLVANIA.

HYDRATION APPARATUS.

1,420,153.

Specification of Letters Patent. Patented June 20, 1922.

Continuation in part of application Serial No. 33,241, filed March 10, 1916. This application filed March 26, 1917. Serial No. 157,300.

To all whom it may concern:

Be it known that I, JOHN C. SCHAFER, a citizen of the United States of America, residing at Tiffin, Seneca County, Ohio, have 5 invented new and useful Hydration Apparatus, of which the following is a specification.

This invention relates to moistening or slaking material, as hydrating alkali earth 10 oxides.

This invention has utility when incorporated in connection with continuous treatment, say of quicklime for conversion to calcium hydrate.

15 Referring to the drawings:

Fig. 1 is a side elevation with parts broken away disclosing an apparatus for use in carrying out the invention;

Fig. 2 is a fragmentary side elevation of 20 the feeding device;

Fig. 3 is a section on the line III—III Fig. 2;

Fig. 4 is a fragmentary view of the discharge device;

25 Fig. 5 is a plan view of the spray devices of the top section or chamber;

Fig. 6 is a vertical section through the upper bearing of the hydrator showing the circulating system;

30 Fig. 7 is a fragmentary perspective view of a corner clearing plow for a movable platform;

Fig. 8 is a fragmentary perspective view of a corner clearing plow for a stationary 35 platform;

Fig. 9 is a detail view of one of the adjustable clearance material agitating and progressing plows; and

40 Fig. 10 is a perspective view of a cone clearing plow.

The hydrator embodies the main housing 1 shown as cylindrical, which carries thereover the feeding device including the hopper 2 delivering to the endless conveyer 45 or belt 3 to effect delivery thereby of a weighed uniform mass of material continuously to the hydrator. This uniform weight of material may be adjusted according to the determined rate desired by manipulation 50 of the scale beam 4.

Driven simultaneously with this continuous feed device for the supply of uniform weight of the material fragments is the moisture supply device being actuated there-

from by the connecting rod 5 the throw 55 of which may be adjusted as desired by the positioning of the wrist pin 6. This varied reciprocation effective for the piston rod 7 determines the feed volume of water supplied from the liquid measuring cylinder 60 8 to the spray pipe 9 extending centrally of the top of the hydrator housing 1 that the branch 10 may deliver to the chamber 11 for passage therefrom through the rectangular spray 12 and radial sprays 13, 14, 65 embodying pipes with series of perforations therein. This chamber 11 is a water circulation cooling chamber for the bearing 15 engaging the upper end of the rotatable central shaft 16 of the hydrator. 70

The branch pipe 17 may supply water directly to the friction faces between the bearing 15 and the shaft 16 for film lubrication, this water passing therefrom over the cone 18 to assist in moistening the lime or other 75 material being treated.

This material supplied from the belt 3 of the feed device enters the scroll conveyer 19 driven by the shaft 20 from a source for operation simultaneously with the 80 driving of the water measure and the material weighing belt. This scroll conveyer 19 has the arch 20' for its upper section, while the lower section conforms to the curvature of the variable pitch scroll. Ac- 85 cordingly, when the material fragments are supplied thereto, such material in this conveyer operates as a seal in precluding escape of gases from the hydrator housing 1. The discharge from this conveyer 19 into the 90 housing 1 is by the chute 21 centrally of the rectangular spray 12 so that the falling fragments are immediately thoroughly mixed with water before they reach the top revolving platform 22 carried by the 95 shaft 16. Should this water supply from the spray 12 be insufficient for the desired hydration, the additional spray arms 13 and 14 may be supplied. In Fig. 5 there is shown an additional spray supply connection 23 which, in instances for still further water supply, may be provided with a spray of the desired form. 100

Carried by the top of the housing 1 and fixed therewith are the radiating arms 24 105 providing sockets for the stems 25 which may be adjusted to the desired angular positions by the set screws 26 and mounted

2
against movement. Pivots connected to the stems 25 are the arms 27 fast with which may be the plow plate 28, the clearance of which may be adjusted as to the 5 platform by the plow arm engaging clamp for chain 29 extending to the hook 30 on the stem 25. These plows may have their angular position varied as desired to determine the progress of the material during 10 hydration and agitation stages for covering the entire platform region.

The hydrated material is more fluffy and accordingly in the agitation incidental to the relative movement of the plows and 15 platform works to the surface of this material. The retarding flange 31 on the platform 22 serves to detain the coarser unhydrated or unslaked portions, while allowing the more thoroughly slaked to work over 20 this flange 31 and fall upon the stationary platform 32. The platform 22 carries on its under side the radiating arms 33 having plows 28 to progress this material from the outer edge of the platform 22 in the 25 opposite direction, or inward, to spill centrally therefrom upon the cone 34 and rotating platform 35. These stages of alternating travel are continued throughout the downward course of the material in this 30 housing 1 until final delivery from the lower platform 36 by the chute 37 to the scroll conveyer 38 for delivery of the slaked or finished dried material.

The scroll conveyer 38 is driven from the 35 sprocket wheel 39 by the sprocket chain 40 from sprocket wheel 41 on the shaft 42, which shaft 42 carries the main drive sprocket 43. On this shaft 42 is the bevel pinion 44 in mesh with the bevel gear 45 40 on the shaft 16 driving the various movable platforms and the plows of these platforms sustaining arms.

Provision is made that the machine or 45 hydrator may be self-cleaning throughout thereby avoiding any caking of stock and its consequent interference with the uniform operation of the apparatus in the production of a standard product of superior quality. In this connection the outer or 50 retarding flange 31 of the moving platform has its angle cleared of stock by the plows 46 mounted upon the brackets 47 carried by the housing 1. The corner clearance for the stationary platforms is effected by the 55 plows 48 carried by brackets 49 connected to a pin 25 carried by a movable platform arm. The cones are cleared by the plows 50 mounted on the carrying brackets 51 fast with the stationary platform arm support.

The superiority of the product, especially in certain calcium and magnesium hydrates is greatly improved by the elimination of inert gases, as air, and the maintenance of

the steam vapor as a blanket independent of circulation and confining such blanket at a certain stage or stages in the chambers of this housing 1. This is effected by allowing the heat from hydration to generate 70 steam, driving off the air, then closing the drafts 52 in the ducts 53 from the desired upper chambers thereby cutting off the direct communication from the upper chambers to the stack 54. This flow from the 75 stack 54 may be checked by the top trap doors 55. The bottom trap doors 56 may serve for clean-out when too strong draft has drawn lime dust into the stack.

With the steam as a blanket trapped in 80 the upper chamber or chambers where the mingling or mixing occurs in the first stages and the agitation for thorough hydration in the succeeding intermediate stages, there is that permeation of the steam throughout the 85 entire mass of material insuring a thoroughness of hydration.

The effectiveness of the initial spray for moisture supply works against the accumulation of the material in balls, while the 90 plows in their action further tend to break up any such gatherings. With the retarding flanges operating to assist in holding back the less-thoroughly hydrated or unslaked stock, the later stages of the hydrator have on their platforms a stock most thoroughly slaked and the dry steam or hot gases from the initial stages co-operate 95 in assisting the drying during the agitation.

With the draft from the hydrator passing 100 over these platforms with the agitated stock excess moisture is removed for at the terminal stages, spill centrally of the platform 36 is precluded by the central flange 57, the opening through which may allow 105 an indraft of air from the man-hole 58, which air may pass up the shafts 54 from the lower chambers of the hydrator. With the heat escape from the upper chambers controlled, the hydrated lime is so hot that 110 upon reaching the lower heat dissipating or cooling and drying chambers, the excess moisture is readily given up to the incoming air establishing an effective cooling and drying draft through the stack.

For common subject matter, this case is a continuation in part of my application Ser. No. 83,241, filed Mar. 10, 1916, issued as Patent No. 1,220,995, March 27, 1917.

What is claimed and it is desired to secure 120 by United States Letters Patent is:

1. A lime hydration apparatus embodying a continuous uniform rate feed device, and means for slaking the lime including a housing having a feed receiving upper section and a water supply upon the lime in the housing upper section to cause slaking reaction with the lime in generating a moist atmosphere, said housing being closed as 125

against vapor escape upward from said upper section for holding said atmosphere as a lime generated steam envelope for the lime.

2. A multichamber lime hydration ap-

5 paratus embodying a continuous feed device for lime, a water supply directed upon the lime, and means for driving water of said supply into the lime during slaking including a chamber closed as against vapor escape 10 upward therefrom for holding the steam generated by the heat of slaking as an envelope for resisting liberation of the moisture by the lime.

3. A multichamber lime hydration apparatus including a closed chamber, a moisture supply for directing water upon the lime in said chamber, and means for progressing the lime through the apparatus, said chamber being closed as against vapor escape 20 cape upward therefrom for holding the steam generated by the heat of slaking as an atmosphere enveloping the lime during the progress of the lime.

4. A multichamber lime hydration apparatus embodying a closed chamber, and definite lime and water proportioning means including relatively adjustable interconnected feeding devices therefor, said chamber provided with means for controlling the enveloping 30 hydration-generated steam atmosphere as a held heat blanket over the lime mixed with water.

5. A lime hydrator embodying a moisture mixing chamber having its upper portion closed to hold generated vapors therein, an agitation chamber to which the mixing 35 chamber delivers including a dam for the unslaked lime which permits the slaked lime to fluff therover, and a drying chamber for the 40 slaked lime.

6. A hydrator embodying a continuous feed device having a discharge, a spray surrounding said discharge, material agitating means for the sprayed material, and a driver 45 for the means.

7. A hydrator embodying a continuous feed device having a discharge, a spray enveloping the discharge, supplemental spray means, material agitating means for the 50 sprayed material, and a driver for the means.

8. A hydrator embodying a housing, a shaft in the housing, a chambered bearing for the shaft, and means for supplying a hydrating liquid in the housing including means 55 providing a passage communicating with the interior of the housing and with the chambered bearing.

9. A hydrator embodying a housing, a shaft in the housing, a chambered bearing 60 for the shaft, and means for supplying a

liquid to the hydrator including means providing a passage communicating with the interior of the housing for flow from the chambered bearing.

10. A hydrator embodying a housing, a shaft in the housing, a bearing for the shaft, and pressure liquid supply means for establishing a water film in said bearing, there being a way permitting flow from said water film into the housing as a water supply 65 for the promotion of hydration.

11. A hydrator embodying a chamber provided with means for maintaining a vapor blanket therein, a continuous feed device embodying movable means for supplying material to the chamber, and a housing about the device, means coacting with said means to hold the material as to the device in forming a packed material seal from the device precluding gas flow from the chamber out 70 through the device.

12. A hydrator embodying a platform, relatively movable means operable in a plane parallel to the platform over the platform, a loosely pivoted plow mounted for dragging after said means, and an adjusting device for determining the plow swing on its pivot as to the means for approximating continuous uniform clearance from the platform in its drag.

13. A hydrator embodying a platform having a cone, a rigidly mounted material clearing plow positively held in fixed position as to said cone, and means for effecting relative movement between the cone and 95 plow.

14. A hydration apparatus embodying a cylindrical housing providing in coaxial alignment a moistening and heat generating chamber closed to hold a vapor blanket therein, an agitation chamber, and a drying and cooling chamber, said chambers being in a series for continuous treatment and each having a floor and power driving means for progressing the material to be hydrated to 100 overflow from the respective floors.

15. A hydration apparatus embodying a housing including heat generating and heat dissipating sections, said heat generating sections being closed to hold a vapor blanket 110 therein, said heat generating section including a moistening chamber and an agitation chamber, said heat dissipating section including a cooling and drying chamber, said chambers being coaxial and each having a 115 floor, and power driving means for progressing the material to be hydrated to overflow from the respective floors.

In witness whereof I affix my signature.

JOHN C. SCHAFFER.
